CLAIM

We claim the ornamental design for the contoured rectangular lid, as shown and described.

DESCRIPTION

FIG. 1 is a perspective view of the lid with the door in the closed position;

FIG. 2 is a perspective view similar to FIG. 1, but with the door in an open position;

FIG. 3 is a top view of the lid as shown in FIG. 1;

FIG. 4 is a top view of the lid as shown in FIG. 2;

FIG. 5 is a front view of the lid as shown in FIG. 1;

FIG. 6 is a rear view of the lid as shown in FIG. 1;

FIG. 7 is a front view of the lid as shown in FIG. 2;

FIG. 8 is a bottom view of the lid as shown in FIG. 1;

FIG. 9 is an enlarged side view of the lid as shown in FIG. 1, taken from the right;

FIG. 10 is an enlarged side view of the lid as shown in FIG. 2, taken from the right; and,

FIG. 11 is an enlarged cross-sectional view of the lid as shown in FIG. 10.

(57) CLAIM

We claim the ornamental design for the contoured rectangular lid, as shown and described.

DESCRIPTION

FIG. 1 is a perspective view of the lid with the door in the closed position;

FIG. 2 is a perspective view similar to FIG. 1, but with the door in an open position;

FIG. 3 is a top view of the lid as shown in FIG. 1;

FIG. 4 is a top view of the lid as shown in FIG. 2;

FIG. 5 is a front view of the lid as shown in FIG. 1;

FIG. 6 is a rear view of the lid as shown in FIG. 1;

FIG. 7 is a front view of the lid as shown in FIG. 2;

FIG. 8 is a bottom view of the lid as shown in FIG. 1;

FIG. 9 is an enlarged side view of the lid as shown in FIG. 1, taken from the right;

FIG. 10 is an enlarged side view of the lid as shown in FIG. 2, taken from the right; and,

FIG. 11 is an enlarged cross-sectional view of the lid as shown in FIG. 10.
